(57) **CLAIM**

The ornamental design for a smart protective mask as shown and described.

DESCRIPTION

FIG. 1 is a perspective view of a smart protective mask showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the circle portion labeled 9 as shown in FIG. 1;

FIG. 10 is an enlarged view of the circle portion labeled 10 as shown in FIG. 1; and,

FIG. 11 is an enlarged view of the circle portion labeled 11 as shown in FIG. 1.

The dash-dash broken lines in FIGS. 1-8 depict portions of the smart protective mask that form no part of the claimed

(Continued)

design. The long dash-short dash broken lines in FIGS. 1 and 9-11 depict boundaries of the enlarged views and form no part of the claimed design.

1 Claim, 11 Drawing Sheets
